PICKER CHECK FOR LOOMS

Horace M. Phillips, Gastonia, N. C.

Application January 31, 1944, Serial No. 520,451

7 Claims. (Cl. 139—167)

This invention relates to a picker check for looms, and more especially to spring means for arresting the picker stick, as it is moving outwardly with relation to the edge of the cloth being woven under impact of an incoming shuttle into the shuttle box.

Heretofore the conventional means for arresting movement of the picker stick has been by means of a check strap which is secured to a bracket on one side of the lay of the loom below the shuttle box, and has its other side portion frictionally engaged by suitable fingers for applying the desired amount of resistance to movement of the check strap to thereby arrest the picker stick. Check straps are usually made of leather, and are therefore very expensive and soon become worn, requiring replacement.

It is an object of this invention to provide a picker stick check comprising a member adapted to be secured to the conventional bracket which heretofore has secured the overlapped ends of the conventional check strap in position, said member having means for adjusting the same relative to the bracket and also for adjusting the same relative to the lay of the loom, and having on one end thereof an adjustable angle member to which is secured an adjustable leaf spring so that the angularity of the leaf spring relative to the member can be adjusted both laterally of the shuttle box and longitudinally of the same.

It is another object of this invention to provide a spring means for arresting the outward movement of a picker stick, said spring means employing the conventional spring which is in common use in many mills in box looms for applying the proper amount of pressure to the binders in the box looms. By providing an arresting mechanism employing such a spring, the mills usually have these springs in stock so that if a spring used as a picker check should become broken, it can be replaced within a very few minutes and operation of the loom can be resumed.

It is a further object of this invention to provide in a loom, a strap iron member adapted to be adjustably secured to the conventional bracket projecting downwardly from the lower portion of the lay of the loom and said strap iron member having adjustably secured thereon a right angle bracket spring holding means and a leaf spring adjustably secured on the right angle bracket for engaging the picker stick in outward travel under impact of the shuttle moving into the shuttle box, together with means for engaging the lower por-

tion of the lay for assisting in stabilizing and supporting the strap iron member which is secured to the conventional downwardly projecting bracket on the lay of the loom.

Some of the objects of the invention having been stated, other objects will appear as the description proceeds, when taken in connection with the accompanying drawing, in which:

Figure 1 is a side elevation of the outer portion of a shuttle box on the lay of the loom, and showing the picker stick engaging the leaf spring for arresting the same;

Figure 2 is a vertical sectional view taken along the line 2—2 in Figure 1;

Figure 3 is a view of the right-hand lower portion of Figure 1 looking from the opposite direction from the direction of view in Figure 1.

Referring more specifically to the drawing, the numeral 10 indicates the lay of a loom having a suitable binder 11 which is usually pivoted as at 11a and which serves to box and apply friction to a shuttle 12, the nose of which usually engages the picker 13, disposed on a picker stick 14 which is pivoted as at its lower end in a conventional manner not shown. The outer end of the shuttle box or the lay usually has a leather strap member 16 against which the picker stick sometimes strikes at its extreme limit of motion. The lay has a suitable slot 17 in which the picker stick 14 has movement. The lay also has secured thereon a conventional bracket 18 by any suitable means such as bolts 19, and this bracket has heretofore been employed for securing the overlapping ends of a conventional check strap.

To the downwardly projecting leg of bracket 18 I secure an elongated straight strap iron member 25 which has an elongated slot 26 therein penetrated by a bolt 27 which also penetrates the downwardly projecting leg of bracket 18 to secure the strap iron member 25 in position. This strap iron member has also a bolt 30 penetrating the same over which the lower forked portion of a bracket 31 is adjustably secured, the upper end 40 of the bracket having an inturned horizontal portion 32 adapted to fit against the lower surfaces of the lay 10 for assisting bolt 27 in supporting the strap iron member 25 in the desired position.

Near the extreme right end of the strap iron member 25 as shown in Figure 1, there is a vertically disposed slot 35 in which a bolt 36 is disposed, said bolt 36 also being disposed in a vertically disposed elongated slot 31 in a right angle member 38 which right angle member 38 is also 45 secured to the strap iron member by means of a

bolt 39 penetrating both the member 38 and the strap iron member 25. This slotted arrangement permits angular adjustment of the member 38 relative to the member 25. The member 38 has a portion 40 disposed at right angles to that portion which lies flush against one side of the strap iron member 25, and this portion 40 has transverse or horizontally disposed slots 41 and 42 in which bolts 43 and 44 are disposed, which bolts also penetrate the shank portion 45a of a leaf spring 45 and the slots 41 and 42 allow for angular adjustment and angular position transversely of the lay of the loom of the spring 45. This spring 45 projects downwardly and inwardly to where its lower end is disposed in the path of the picker stick 14, and when an incoming shuttle is driving the picker stick outwardly in the shuttle box, the picker will engage the lower end of the leaf spring 45 which will gradually arrest the same and thus this arrangement entirely replaces the conventional check strap for looms.

In Figure 1, the picker stick in its outward travel has already engaged the lower end of the spring 45, and has flexed it to a certain degree, but the picker stick has not as yet quite reached the limits of its outer travel. It is, of course, evident when the picker stick is projected to the other end of the shuttle box that in expelling the shuttle from the shuttle box that the lower end 45b of the spring 45 will flex further to the left in Figure 1 and be ready to receive and engage the picker stick as it again travels outwardly in the shuttle box upon receipt of an impact from an incoming shuttle into the shuttle box.

The type of spring 45 which is shown is of the type used in box looms as a binder spring and as such, it has a concavo-convex shank portion 45a and a straight leaf portion 45b on its lower portion, the shank portion 45a giving rigidity to that portion which is penetrated by the bolts, and the portion 45b flexes under the impact of the picker stick as it is thrown against the lower end of the end portion 45b of the spring.

It is evident that due to the separability between part 25 and part 38 and the removability of member 31 that this mechanism can easily be adapted for either side of the loom or for either end of the loom as the member 31 can be removed from bolt 30 and turned 180°, or reversed as to its side, and the member 38 can be taken off and inverted together with its spring and placed again on the strap iron member 25. Also the spring 45 being removable, it can be turned to a 180° position from the position shown in Figure 1 should it be desired to attach this mechanism to the other side of the lay or to the other end of the loom. Thus, I have provided a picker stick arresting apparatus which can be placed on either side of the lay of the loom or at either end of the lay without the necessity of having a special type of mechanism for each end of the lay, or for either side of the lay, and thus the mechanism is easily adaptable to all types of looms and for either end of a loom.

In the drawing and specification, there has been set forth a preferred embodiment of the invention, and although specific terms are employed, they are used in a generic and descriptive sense only and not for purposes of limitation, the scope of the invention being defined in the claims.

I claim:

1. A picker stick check for looms comprising a member secured below the lay of the loom and

adjustable longitudinally of the lay of the loom and having a right angle member adjustably secured for vertical adjustment on its outer end, a leaf spring member adjustably secured for lateral adjustment on the right angle member and projecting downwardly and having its lower end adapted to be engaged by the picker stick during its outward motion in the shuttle box.

2. In a loom having a shuttle box, a picker stick, and a bracket projecting downwardly from one side of the lay of the loom, an elongated member secured on said bracket, and extending to a point below the outer end of the lay of the loom, a right angle member adjustably secured on the outer end of said elongated member for vertical adjustment and a leaf spring adjustably secured at its upper end on the right angle member for lateral adjustment and projecting downwardly and having its lower end adapted to engage the picker stick in its outward motion in the shuttle box.

3. In a loom having a lay, a shuttle box, and a picker stick having a picker thereon adapted to be engaged by a shuttle upon entering the shuttle box to force the picker stick outwardly in the shuttle box, means for arresting the travel of the picker stick under the impact of the shuttle comprising a member secured below the lay of the loom and to one side of the path travelled by the picker stick and projecting outwardly and having a right angle portion projecting beneath the outer end of the lay of the loom, said right angle portion being adjustable on a horizontal pivot, the plane of which extends transversely of the path travelled by the picker stick, and a leaf spring member adjustably secured on the right angle member and having its lower end projecting downwardly into the path of the picker stick as it is propelled outwardly in the shuttle box by the impact of the shuttle.

4. A picker stick check for looms comprising a member secured below the lay of the loom and adjustable longitudinally of the lay of the loom and having a right angle member adjustably secured on its outer end, a leaf spring member adjustably secured on the right angle member and projecting downwardly and having its lower end adapted to be engaged by the picker stick during its outward motion in the shuttle box, and a bracket adjustably secured to the first member and having its upper end contacting the lay to assist in supporting the first member.

5. In a loom having a shuttle box, a picker stick, and a bracket projecting downwardly from one side of the lay of the loom, an elongated member secured on said bracket, and extending to a point below the outer end of the lay of the loom, a right angle member adjustably secured on the outer end of said elongated member and a leaf spring adjustably secured at its upper end on the right angle member and projecting downwardly and having its lower end adapted to engage the picker stick in its outward motion in the shuttle box, and a bracket adjustably secured to the elongated member and engaging the lay to assist in supporting the elongated member.

6. In a loom having a lay, a shuttle box, a picker stick, and a bracket secured to and projecting downwardly from one side of the lay, a strap iron member adjustably secured on said bracket and extending outwardly and having a right angle portion extending beneath the lay, a leaf spring member secured on said right angle portion, and projecting downwardly and having its lower end positioned to be engaged by the

picker stick in its outward motion upon receipt of a shuttle into the shuttle box, and a bracket adjustably secured on the strap iron member and engaging the lay.

7. In a loom having a lay, a shuttle box, and a picker stick having a picker thereon adapted to be engaged by a shuttle upon entering the shuttle box to force the picker stick outwardly in the shuttle box, means for arresting the travel of the picker stick under the impact of the shuttle comprising a member secured below the lay of the loom and to one side of the path travelled by the picker stick and projecting out-

wardly and having a right angle portion projecting beneath the outer end of the lay of the loom, said right angle portion being adjustable on a horizontal pivot, the plane of which extends transversely of the path travelled by the picker stick, and a leaf spring member adjustably secured on the right angle member and having its lower end projecting downwardly into the path of the picker stick as it is propelled outwardly in the shuttle box by the impact of the shuttle, and a bracket secured on the first member and having its upper end contacting the lay.

HORACE M. PHILLIPS.
